UNITED STATES PATENT OFFICE.

JAMES M. BRYANT, OF BENWOOD, WEST VIRGINIA, ASSIGNOR OF TWO-THIRDS TO PETER ALTMAYER AND CHRISTIAN ALTMAYER, BOTH OF SAME PLACE.

NAIL-PLATE FEEDER.

SPECIFICATION forming part of Letters Patent No. 355,584, dated January 4, 1887.

Application filed October 2, 1886. Serial No. 215,159. (No model.)

To all whom it may concern:

Be it known that I, JAMES M. BRYANT, of Benwood, in the county of Marshall and State of West Virginia, have invented a new and useful Improvement in Nail-Plate Feeders; and I do hereby declare that the following is a full, clear, and exact description of the same.

My invention is an improved organization of mechanical elements designed to automatically feed the blanks from which nails are formed to the cutters of a nail-machine.

My invention belongs to that particular class of machines in which the barrel for holding the nail plate or blank is carried upon a pivoted support and oscillates to and from the cutters, being given a half-turn during the intervals between the cutting operations to present opposite sides of the blank alternately to the knives.

My object is to produce a perfectly automatic machine having all the movements necessary to the effective accomplishment of the work, the various operating parts being organized in a simple compact form.

My invention consists in the special construction and arrangement of the operative parts, all of which will be hereinafter described and claimed.

In the accompanying drawings, Figure 1 is a side elevation of the device. Fig. 2 is a perspective view of the feeder. Fig. 3 is a plan view of the barrel and feeding mechanism.

In the drawings, A represents the bed of the machine, and B the shaft, supported in suitable standards, 1 2. The stationary cutter is shown at C. To the front end of the bed an arm, D, is pivotally supported in suitable ears, 3 and 4, so as to have an oscillatory movement when operated by the driving power. The upper end of this arm is formed into a journal-box, in which is carried a barrel, D', of substantially the same interior construction as is usual in these devices. The barrel is journaled in a proper manner to have rotary movement for the purpose of turning the nail-blank to present opposite sides to the cutters. The nail-blank passes through suitable projecting fingers secured to the tapering front end of the barrel in the usual manner, and is held in central position by means of the rod 5, supported at its rear end by the forked standard 6.

I aim to simplify the construction of the device by employing the oscillating arm D as a support for as many of the operating parts as the requirements of the apparatus will permit. 55 I also aim to derive all the necessary movements from a single cam-surface through connections few in number and arranged in the most compact form.

The first movement to be effected is the oscillation of the barrel on its pivot, whereby the nail-blank is first moved upwardly and away from the cutters after each cutting operation, for the purpose of allowing the blank to be turned to present its opposite sides to 65 the knives, and then returned to its former position to allow the cutting to be performed. This movement is accomplished by the arm 7, one end of which is connected to the upright post on the journal-box, the other end terminating in a yoke, within which the cam E plays. During the movement of the barrel away from and back to the cutters the half-revolution of the barrels with the nail-blank takes place, and this is done through the medium of the 75 following mechanism:

The portion 8 of barrel situated outside of the bearing is provided with four teeth, which are engaged alternately by pull and push pawls 9 and 10, each having movement enough to 80 give the barrel a quarter-turn in the same direction. These are carried upon the upper end of an arm, F, pivoted upon the front side of the oscillating post D. The connection between the pawls and the arm is made by means 85 of a long pin, 10^a, which passes through these parts and projects a sufficient distance beyond to be acted upon by a forked lever actuated by the cams on the shaft. This arm is shown at 11, and is secured to a rock-shaft, G, journaled in suitable bearings in the bed of the machine and extending to the rear slightly beyond the main shaft. An arm, f, is secured to the rear end of this shaft, extending laterally, so as to engage with a vertically-arranged 90 link, H, by which its end is raised and lowered to rock the shaft. The operating-cam on the main shaft is employed to give this link the necessary vertical movement, and for this purpose the cam-yoke, heretofore mentioned, has 95 a rearwardly-extending arm, m, positioned directly opposite to the arm 7, connecting the 100

yoke with the oscillating arm. To the outer end of this arm the upper end of the vertical link is pivotally connected. A slot is formed vertically in the link; adapted to receive a pin, 5 *n*, projecting from a suitable standard on the frame, whereby the link is guided and steadied in its movement. It will be observed that the link, besides having the necessary vertical movement, will also receive a vibratory movement resulting from the revolution of the cam, and in order to render this movement of the link ineffectual as to imparting any motion to the rock-shaft, I enlarge the lower end of the lever and form therein a curved slot struck 10 from centers situated at the ends of the vertical slot in the link. The end of the arm *f* projects into this slot, and as the link swings from side to side no movement will be imparted thereto, but when the high part of the cam 15 moves to raise or lower the link the sides of the slot will bear upon the end of the arm and move it accordingly.

From this construction, by which the two movements referred to are derived from one 20 cam-surface through connections arranged to be operated in different parts of the movements of said cam, I secure a simple device, and the several motions must follow one another in their proper order.

30 The movement of the cam and its connections to the oscillating arm *D* and the pawls are all so timed that when the arm *D* moves backward the shaft will be rocked in one direction, and one of the pawls operated to partially rotate the barrel, and when the reverse movement of the arm takes place the shaft will be returned, and the other pawl thrown into action to complete the necessary half-turn. The connecting-pin between the pawl and its 35 operating-arms is long enough to remain in engagement with the forked arm at all parts of the movement of the arm *D*.

To feed forward the nail-blank at the proper moment I have provided clutches *a*, *b*, conveniently positioned upon either side of the barrel to grasp the edges of the blank when the half-turn of the same has been effected and the barrel moves forward to place the blank in position for the cut. These nippers or 45 clutches are carried upon the bifurcated upper end of a lever, *I*. I pivot the lever to the oscillating arm *D* on the rear side thereof in the space, as shown, below the rear end of the barrel. It is pivoted near its lower end, and is 50 provided with a screw-threaded push-pin, *c*, adapted to strike the frame on the forward throw of the oscillating arm, and thus impart a movement to the clutches in advance of the forward movement of the barrel. The push-pin 55 may be adjusted to increase or diminish the amount of feed. It is essential that sufficient space be left between these clutches to allow the blank to be turned without striking, and that as soon as the turn is completed the 60 edges should be grasped by the clutches to effect the proper feed on the forward movement.

of the barrel. For this purpose one of the clutches is pivotally connected to its supporting-arm, its forward arm being constantly acted upon by a spring, *r*, tending to push it 70 away from the blank. During the turning of the blank this tendency is not resisted and the blank turns freely; but when the arm *D* moves forward and the clutches receive a movement in advance thereof the enlarged 75 cam-shaped tail-piece *o* of the clutch rides upon a cam-projection, *p*, on the journal-box, and causes the forward end of the clutch to press hard against the blank, so that it may be fed positively forward. 80

It may be observed that as the arm *7*, projecting from the front of the yoke, is pivoted to the post on the arm *D*, the proper movement of the rearwardly-extending arm *m*, with its link, is secured, the pivot-point 13 acting as a 85 center, whereby the movement is steadied and governed. By utilizing the arm *D* as a support for the two operating-levers shown, I make a very compact form of apparatus, for these parts occupy the space below the projecting 90 ends of the barrel and are entirely out of the way.

Having thus described my invention, I claim—

1. In a nail-plate-feeding machine, and in 95 combination, a revoluble barrel, *D*, teeth formed on the periphery of said barrel, push and pull pawls 9 and 10, an oscillating support for said pawls, and mechanism, substantially as described, for operating said support, whereby 100 the pawls act alternately upon said teeth, substantially as described.

2. The combination, with the revoluble barrel *D'*, of a nail-plate feeder having teeth formed thereon, push and pull pawls 9 and 10, acting 105 upon said teeth and carried by an oscillating support, a cam on the main shaft, a shaft or its equivalent actuated alternately by the high and low parts of the cam, connections between the said pawl-support and the said shaft, an 110 oscillating supporting-arm for the barrel, a connection thereto actuated alternately by the high and low parts of said cam, whereby when the arm moves in one direction one pawl will be operated and when in the opposite direction the other pawl will be operated, substantially 115 as described.

3. In a nail-plate feeder, and in combination, a revoluble barrel, *D'*, an oscillating supporting-arm, *D*, therefor, mechanism carried by 120 said arm for operating the barrel, a rock-shaft, *G*, and connections for actuating said mechanism, cam mechanism on the shaft *B*, and connections between said mechanism and the rock-shaft, consisting of a link, *H*, and arm *f*, substantially as described. 125

4. In a nail-plate feeder, and in combination, a revoluble barrel, *D'*, an oscillating supporting-arm, *D*, therefor, nippers for feeding forward the nail-plate arranged to act directly 130 upon said plate, the supporting-lever *I* for said nippers, pivoted to the oscillating arm *D*, the

cam-shaped tail-piece on the pivoted lever, and the enlargement on the oscillating arm D, all substantially as described.

5. In a nail-plate feeder, and in combination, a revoluble barrel, D', an oscillating supporting-arm, D, therefor, push and pull pawls, an arm, F, for carrying the same pivoted to one side of the arm D beneath the projecting end of the barrel, nippers for feeding forward the blank, and a supporting-lever, I, therefor pivoted to the other side of the arm D beneath the opposite end of the barrel, all substantially as described.

10. In a nail-plate feeder, and in combination, a revoluble barrel, an oscillating arm, D, for supporting the same, mechanism for operating the barrel, a cam on the shaft B, a yoke actu-

ated thereby, an arm, 7, projecting from said yoke and connected to the oscillating arm, and an arm, m, projecting from the opposite side 20 of said yoke for operating the barrel-revolving mechanism, substantially as described.

15. In combination with the vertically-movable link, a yoke having a projecting arm, m, connected thereto, an oscillating arm, D, and 25 an arm connecting said yoke with arm D, substantially as described.

In testimony whereof I have signed my name to this specification in the presence of two subscribing witnesses.

JAMES M. BRYANT.
